UNITED STATES PATENT OFFICE

EDWARD L. MACK, OF NORTH TARRYTOWN, AND CHARLES W. BENNETT, OF DOUGLASS-
TON, NEW YORK, ASSIGNEES TO BENNETT-MACK CORPORATION, OF DOUGLASTON,
LONG ISLAND, NEW YORK, A CORPORATION OF NEW YORK

EMULSION

No Drawing.

Application filed March 7, 1930. Serial No. 434,178.

This invention relates to a composition of matter, and a method of producing the same, in the form of an emulsion to be applied to the face for shaving purposes.

5 The object of this invention is to produce a finished emulsion particularly useful as a shaving preparation or as a preparation for the skin which is more effective for the purpose than preparations now used, thereby increasing efficiency.

With this and other objects in view, the invention consists in the novel composition of matter or emulsion, as well as the novel steps and combination of steps constituting the 15 process by which it is produced, all as will be more fully hereinafter disclosed and particularly pointed out in the claim.

In order that the precise invention may be more clearly understood, it is said: Formerly, the generally used practice in shaving was to apply to the area to be shaved, or make thereon, a lather or foam of soap and water. As a working hypothesis to explain the generally accepted use of soap lather in shaving, 20 it may be said that it provided the most readily available material which combined the properties of softening the hair and furnishing a degree of mechanical support for the same so that it might be cut by the razor. 25 Preparations for this purpose belong, therefore, to the lathering type.

Latterly, emulsions of the oil-in-water type were introduced to replace the soap lather. These preparations belong to the latherless 30 type, since no foam or lather is produced. As compared with soap lather, these emulsions appear to have at least as great softening power, and greater supporting power.

Our study of the operation of shaving has 35 led to the following conclusions:

1. The passage of the razor over the face is unavoidably conducive to the production of minor abrasions of the skin. These are largely of a cutaneous or superficial nature, rather than sub-cutaneous. They are not of such a gross nature as to be visible to the naked eye, in most part, but consist of a multiplicity of small trauma of the skin.

2. Soap is irritating to such abraded or 40 traumatized surfaces.

3. The oil-in-water latherless emulsions used for shaving usually contain soap and are therefore irritating to such abraded or traumatized surfaces, although somewhat less so than straight soap lather. 55

4. Shaving with either of the above mentioned types of shaving preparations is accompanied by rubefaction and irritation of the skin, which condition persists after the completion of the shaving operation. 60

5. It is common practice with shavers to allay this irritation and the resulting discomfort by the application of lotions, skin balms, or other emollients. 65

6. Our finding as to the irritating effect 65 of soap on abraded or traumatized skin surface is in accord with the generally accepted theory of selective adsorption.

In the invention now to be described, all the above objections are done away with, as 70 will presently appear. That is to say, we have discovered that shaving preparations may be improved by avoiding the presence therein of soap, and by incorporating therein the proper emollients. We have further discovered that a large part of the discomfort and skin irritation connected with shaving is avoided or allayed by the use of our improved preparation which has incorporated therein one or more substances having local 75 anaesthetic properties. We have added local anaesthetics to some of the emulsions in common use at present and have found that the shaving operation is much more satisfactorily carried out with the modified preparations. This applies to both types of preparations, i. e., the lathering or soap type and the latherless or oil-in-water emulsion type. 80

Substances having local anaesthetic properties are classified by pharmacologists into 90 three groups, as follows:

1. Natural anaesthetics such as benzoyl-1-ecgonine methyl ester.

2. Water soluble synthetics such as diethyl-amino-ethyl-p-amino-benzoate hydrochloride. 95

3. Difficultly soluble derivatives of benzoic acid such as ethyl-p-amino benzoate, propyl-p-amino benzoate.

We have discovered that one or more rep- 100

representatives of the above groups may be beneficially used in our improved preparation, but our preferred practice is to use one or more members of the third group, and particularly ethyl-p-amino benzoate, or any ester of amino benzoic acid or derivatives thereof. Using ethyl-p-amino benzoate as a preferred member of this group, we find that it is non-irritant and non-toxic. In support of this, Braun-Harris in "Local Anæsthesia" (1924 edition) page 111, says "This agent, (ethyl-p-amino benzoate) according to Binz and Kobert, is non-toxic and according to the reports of von Noorden and Lingemann can be used for anæsthetic purposes in the same manner as orthoform, relieving pain for a considerable period without the secondary effects observed following this drug in cases of nervous hyperesthesia of the stomach and ulcus ventriculi. It should be taken ten to fifteen minutes before eating, 2.5 grams being considered the maximum daily dose . . . Injurious secondary effects have never been noticed".

25 The Dispensatory of the U. S. A., (21st Ed. 1926, pages 83-84) says "ethyl amino benzoate is remarkable among the local anæsthetics first for its comparative insolubility and second for its lack of toxicity . . . 30 Kennel has reported a case in which 40 grains were administered to a patient without apparent ill-effect . . . the anæsthetic effect is almost entirely on the nerve terminals; that is, it has very little effect on the nerve trunks 35 as compared for example to cocaine".

We have discovered that especially ethyl-p-amino benzoate, when incorporated in our improved emulsion or preparation exercises sufficient anæsthetic effect to notably decrease 40 the discomforts and irritation attendant upon the ordinary shaving operation, as well as to almost entirely eliminate the distressing after effects.

In order to prepare our improved shaving 45 preparations, we proceed in the following manner:

A fat phase is prepared by melting together at 112 degrees cent. 9 to 12 parts of stearic acid, 6 to 8 parts of cocoanut oil, 50 6 to 8 parts of paraffine wax, and 0.15 to 0.20 parts of zinc stearate. The mixture is cooled to 75 degrees cent., and 0.8 to 3 parts of ethyl-p-amino benzoate dissolved therein. The temperature of the mixture is then lowered to 60-65 degrees cent.

A water phase of the following composition is then prepared. 5.5 to 7.5 parts of glycerine, 0.8 to 1.1 parts of borax, 0.3 to 0.4 parts of ammonia, are dissolved in 56-75 60 parts of water. The temperature is raised to 50-60 degrees cent. This water phase is gradually added to the above fat phase, the latter being continuously and thoroughly stirred in a manner to assist in emulsification, 65 all in accord with practices familiar and well

known to those skilled in the art of emulsion making. A perfume consisting of 2½ gms. of a bouquet perfume, 1½ gms. of bay oil, and 1 gm. of menthol may be added to the finished emulsion, to the extent of 0.2 to 0.25 70 part.

We may substitute other local anæsthetics in the above emulsion or we may use two or more in combination. Thus for example we may take the above emulsion which is anæsthetic or has local anæsthetic properties, and in order to make the anæsthetic properties more pronounced, we may add one or more local anæsthetics to the already anæsthetic emulsion. Or the extra anæsthetic may be added during the process of making. For instance we may use propyl-p-amino benzoate in combination with ethyl-p-amino benzoate, or we may use a member or members of the other groups or types as benzoyl-1-ecgonine methyl ester or di-ethyl-amino-ethyl-p-amino benzoate hydrochloride. The emulsion may be made as strongly anæsthetic as desired, as for example the use of 5 per cent of ethyl-p-amino 80 benzoate causes almost complete anæsthesia of the skin. With di-ethyl-amino-ethyl-p-amino-benzoate hydrochloride or benzoyl-1-ecgonine methyl ester, much smaller quantities are required. 85

While the above formula is our preferred composition, it is obvious that those skilled in the art of emulsion making may vary the proportions of the ingredients as much as fifteen percent in either direction, without substantially altering the properties of the resulting emulsion, and hence without departing from the spirit of our invention. It is also evident that one skilled in the art may substitute for some of the constituents 100 other substances of similar properties, with the result that emulsions will be produced having the novel properties which we have discovered, as will be more fully pointed out in the claim. To illustrate, stearic acid may 105 be substituted by an equivalent amount of other fatty acids, e. g. palmitic. Cocoanut oil may be substituted by other vegetable oils of approximately the same melting point, e. g. palm oil. For paraffine, there may be 110 substituted other waxes of approximately the same melting point, e. g. spermaceti. Zinc stearate may be substituted by any agent tending to produce an emulsion of the water-in-oil type, as for instance the oil-soluble 115 soaps, e. g. magnesium oleate. For ethyl-p-amino benzoate there may be used other non-toxic local anæsthetics, e. g. other members of the group of difficultly soluble derivatives of benzoic acid, as propyl-p-amino benzoate, 120 or members of the other groups given above, as for instance di-ethyl-amino-ethyl-p-amino-benzoate hydrochloride. Glycerine may be substituted by glycols of suitable properties, e. g. ethylene glycol. Borax may be sub-

125
130

stituted by other soluble alkali borates, e. g. potassium or ammonium borate. For ammonia there may be used an equivalent quantity of a substituted amine, e. g. one or more of the ethanol amines.

5 An emulsion of similar appearance may be made from the above formula, omitting the zinc stearate; or omitting the agent for emulsifying water in oil, but we have found that 10 such an emulsion lacks the peculiar quality or body which the presence of the water-in-oil emulsifier confers, and this property we have found advantageous in shaving preparations. This novel property persists in our 15 improved emulsion, not only in the mass, but more especially when the emulsion is spread out and worked onto the area to be shaved.

The oil-in-water emulsifying agent is furnished by the inter-action of the ammonia 20 with the stearic acid. It is pointed out that the calculated ratio of acid to base in the water phase shows 10-15 percent excess of boric acid over the stoichiometric ratio as orthoborates. We have discovered that the 25 emulsion is stabilized by the addition of borax. In other words, if the borax is omitted the emulsion loses ammonia progressively, becoming unstable, with a loss of properties.

30 It is to be noted that the emulsion made by our preferred formula is a double emulsion and contains both water-in-oil and oil-in-water emulsifying agents, with an excess of the latter, furnishing a medium which 35 will obviously take up either oil or water to an extent, without serious change in the property of body or viscosity. This furnishes an agent, therefore, which will take up both oil and water which may surround 40 the hair, and still furnish superior supporting power to hold the hair for the shaving operation.

Our improved preparation is used in the same manner as the oil-in-water types referred to above. It is spread over the wetted 45 surface to be shaved and worked onto this area. The shaving is done with a wetted razor.

50 Menthol is used in our preparation as a perfume. We do not claim its use, being aware that shaving preparations have been made containing menthol in sufficient quantity to stimulate the nerves for the perception of cold and by so doing tending to lessen 55 the immediate discomfort in shaving by accentuation of another sensation, namely, the perception of cold.

It is obvious that those skilled in the art 60 of emulsion making may vary the composition of our shaving preparation or emulsion, and the conditions and details of producing the same, without departing from the spirit of our invention, and we do not wish to be limited to the above disclosure except as may be required by the claim.

What we claim is:—

An emulsion substantially devoid of an alkali soap and composed of

	Parts
Stearic acid	9. to 12.
Cocoanut oil	6. to 8. 70
Paraffine wax	6. to 8.
Zinc stearate	.15 to .20
Ethyl-p-amino benzoate	.80 to 3.00
Glycerine	5.50 to 7.50
Borax	.80 to 1.10 75
Ammonia	.30 to .40
Water	56. to 75.

In testimony whereof we affix our signatures.

EDWARD L. MACK.

CHARLES W. BENNETT.
